UNITED STATES PATENT OFFICE.

ELLIS B. RIDGWAY AND WILLIAM H. RIDGWAY, OF COATESVILLE, PENNSYLVANIA.

STEAM HYDRAULIC ELEVATOR.

1,260,057.

Specification of Letters Patent. Patented Mar. 19, 1918.

Application filed October 6, 1914. Serial No. 865,404.

To all whom it may concern:

Be it known that we, ELLIS B. RIDGWAY and WILLIAM H. RIDGWAY, citizens of the United States, and residents of Coatesville, 5 county of Chester, State of Pennsylvania, have invented certain Improvements in Steam Hydraulic Elevators, of which the following is a specification.

One object of our invention is to make an 10 elevator of the type illustrated so that it will be quick in action, especially when the car or cage is at the upper landing so that when the mechanism is reversed to allow the car to descend it will immediately act.

15 A further object of the invention is to provide means for regulating the impulse given the piston in its upward movement.

A still further object of the invention is 20 to provide means for properly lubricating the main cylinder.

In the accompanying drawings:

Figure 1 is a diagrammatic view of an 25 elevator and its mechanism illustrating our invention;

Fig. 2 is an enlarged view with the main cylinder in section and illustrating the operating mechanism;

Fig. 3 is an enlarged sectional view of the lower portion of the main cylinder on 30 the line *a—a*, Fig. 2;

Fig. 4 is a longitudinal sectional view of the admission valve;

Fig. 5 is a sectional view on the line *b—b*, Fig. 4;

Fig. 6 is a sectional elevation on the line *c—c*, Fig. 7; and

Fig. 7 is a sectional view on the line *d—d*, Fig. 6.

Referring to the drawings, 1 is the main 40 elevator cylinder in which is mounted the piston 2, of the ordinary type, having a rod 3 which projects through the head 4 of the cylinder. This rod has, in the present instance, at the upper end a wheel 5 around 45 which passes the hoisting rope 6 attached at one end to a fixed point 7 and which passes around sheaves 8 and 9 and attached to the cage 10 in the ordinary manner. This cage is adapted to the usual guides.

12 is a steam cylinder located at one side 50 of the main cylinder 1 and 13 is a pipe leading from the bottom of the cylinder 12 to the top of the main cylinder 1 and in this pipe is a controlling valve 14 constructed as 55 clearly shown in Figs. 6 and 7, and which will be described in detail later. A lever

15 is attached to the movable portion of the valve and to a controlling rope 16 which is adapted to suitable guides and is located within easy reach of the operator. 17 is a 60 steam supply pipe leading from a boiler, or other suitable source of supply, to a valve casing 18 which communicates with the upper end of the cylinder 12 and also communicates through a pipe 20, with the lower 65 end of the main cylinder 1. This valve 18 is made as clearly shown in Figs. 4 and 5, and will be described later in detail.

On the stem 19^a of the valve 19 in the casing 18 is an arm 21, which is connected 70 by a rod 22 with the lever 15 of the valve 14 so that the two valves are actuated, in the present instance, in unison. Also communicating with the lower end of the main cylinder 1 or directly with the pipe 20 is an 75 exhaust pipe 23 having a valve 24, which can be used as a regulating valve to increase or diminish the impulse in the piston 2 when steam is admitted to the under side of the piston from the pipe 20. At the lower 80 end of the pipe 23 is a bleeder 25 to free the pipe of any water of condensation.

The cylinder 1 is closed at the lower end and, consequently, it is difficult to lubricate the walls of the cylinder. We, therefore, 85 form a cup 26, Fig. 3, in the bottom of the cylinder and locate on the outside a reservoir 27, which communicates with the cup through a pipe 28. The passage of oil is regulated by a valve 29. In order to spray 90 the oil on the inner walls of the cylinder, we provide a steam pipe 30, which extends into the cylinder and has a downwardly extending nozzle which is directly above the cup. A valve 31 controls the passage of steam to 95 the nozzle. When it is desired to lubricate the interior of the cylinder, a certain amount of oil is admitted to the cup. The steam valve is opened and the steam escapes and forces the oil out of the cup, spraying it 100 against the side wall of the cylinder and thoroughly lubricating the wall. Air may be used in place of steam if found desirable.

The valve 14 is made as clearly shown in 105 Fig. 6, and has passages 32 and 33 forming a continuation of the pipe 13 and in the casing is a valve 34 secured to a stem 35 to which is attached the lever 15 for actuating the valve.

The valve 18 is made as clearly shown in 110 Figs. 4 and 5, and has a central port 36 and

side ports 37 and 38 communicating respectively with the pipes 17 and with the pipe 20. The central port communicates with a pipe 39 which is attached to the upper end of the cylinder 12.

19 is a rotary valve having a port which at all times communicates with the central port 36 of the casing, or with either of the ports 37 or 38.

10 Steam is admitted to the cylinder 12 through the pipe 17 at about one hundred pounds pressure, but in the construction prior to our invention when the elevator car was at a landing the piston 2 was released 15 and there was usually several moments hesitation before the car commenced to descend, due to the fact that the steam pressure in the cylinder 12 would have to be reduced by exhausting before the piston 2 could be 20 raised. This made this type of elevator objectionable where rapid movement was necessary. By coupling the upper end of the steam cylinder with the lower end of the main cylinder, as illustrated in the drawings, the pressure in the steam cylinder 12 at 25 the moment the exhaust takes place is immediately transmitted for an instant to the under side of the piston 2 in the main cylinder 1 and an upward impulse is given to the 30 piston which causes the cage or car to descend immediately. As the one hundred pounds pressure is then on both sides of the piston 2, the pressure is equalized and the car descends by its own weight, owing to the 35 fact that the pressure in the cylinder 12 is reduced as heretofore. The valve 24 in the exhaust pipe can be adjusted so as to regulate the impulse in the cylinder.

While we have mentioned steam as the 40 pressure medium, it will be understood that compressed air may be used instead of steam. The objection to using compressed air has been that compressed air, when released, is apt to freeze at the end of the exhaust pipe, but 45 if compressed air is used in connection with the mechanism above described, the liquid in the cylinder 12 will be heated by the compression of the air above it and this warm

liquid will pass to the cylinder 1 above the piston and the heat will be transmitted to 50 the walls of the cylinder 1, so that when the valve 18 is opened to allow the air to pass through the pipe 20 into the lower end of the cylinder, the cool air admitted to the cylinder is immediately warmed by the cylinder walls and when it passes through the exhaust pipe 23, its temperature is above freezing and, consequently, there is no frost at the exhaust.

Any suitable air compressor may be used 60 and it can be located at any point desired.

We claim:

The combination in an elevator, of a cylinder; a piston therein; a rod connected to the piston; a cage, or car, to which the rod 65 is also connected; a pressure cylinder; a pipe forming communication with the upper end of the main cylinder and the lower end of the pressure cylinder; another pipe forming a communication with the upper end of 70 the pressure cylinder and the lower end of the main cylinder; an impeded exhaust pipe open to the atmosphere, also communicating with the lower end of the main cylinder; a supply pipe from a boiler communicating with the upper end of the pressure cylinder; an admission valve arranged to admit steam to the pressure cylinder and to exhaust steam from the cylinder into the pipe communicating with the lower end of 80 the main cylinder so that when the piston is in the lower portion of the main cylinder and steam is in the reservoir, said steam can be momentarily discharged under the piston in the main cylinder so as to give it an initial 85 movement to cause the cage to start quickly on its descent.

In testimony whereof, we have signed our names to this specification, in the presence of two subscribing witnesses.

ELLIS B. RIDGWAY,
WILLIAM H. RIDGWAY.
